[57] CLAIM

The ornamental design for an article support stand, substantially as shown and described.

DESCRIPTION

FIG. 1 is a side perspective view of an article support stand showing my design;

FIG. 2 is a perspective view thereof showing the side not shown in FIG. 1;

FIG. 3 is a top plan view;

FIG. 4 is a bottom plan view; and

FIG. 5 is a side elevational view; and

FIG. 6 is a front elevational view thereof.
